UNITED STATES PATENT OFFICE.

RICHARD M. IVERSON, OF ROCK ISLAND, ILLINOIS.

PLOW.

1,390,615.

Specification of Letters Patent. Patented Sept. 13, 1921.

Application filed March 23, 1920. Serial No. 368,086.

To all whom it may concern:

Be it known that I, RICHARD M. IVERSON, a citizen of the United States, residing at Rock Island, in the county of Rock Island 5 and State of Illinois, have invented certain new and useful Improvements in Plows, of which the following is a specification.

This invention relates to plows of the kind provided with shares which are detachably held in place by locking devices of such kind that while they firmly connect the share with the frog, mold-board and land-side of the plow they may be easily detached therefrom when required.

In the case of gang plows, it is very difficult to reach the bolts, nuts, etc., which secure the share in place when the latter is held by the old methods, such as by bolts and nuts, and various devices have been suggested and some used for securing the share in place which may be operated without turning over the gang of plows or lifting the gang from the ground. My invention relates to plows of the kind just mentioned, and my object is to provide means for securing the share to the plow which shall be not only easily operated but which shall also be strong and durable.

In carrying out my invention, I secure the land-side to the frog or bottom block of the beam or standard in any suitable way, and I secure the mold-board to the frog or block by suitable devices, and also provide a brace extending from the land-side to the mold-board. This brace is formed with an extension having an end portion projecting from the mold-board having a slot to receive a projection on the share. The block or frog is also slotted to receive another projection on the share in the manner hereinafter described.

The plow share may be of the usual shape but it is provided with a lateral projection which engages a slot in the brace and another projection which engages the slot in the frog and it is also provided with a finger which engages the edge portion of the frog and bears against the land-side and the mold-board in such manner as to bind these parts firmly together.

In order to draw the share into place and lock it in position, I provide a lever which is pivotally mounted on the mold-board and which operates a connecting rod having a loop which engages one of the projections on the share. This rod is so connected with

the lever that when the lever is turned inward it serves to firmly hold the rod under tension and thus firmly hold the share in place. The lever is provided with an arm 60 which engages a bracket, serving as a brace to the lever, to prevent it from bending sideways, and a stop is provided for limiting the downward or inward movement of the lever.

The projection on the plow share which is engaged by the looped end of the connecting rod is so constructed and attached to the share that it cannot be moved out of place even when placed under great strain. Preferably this projection consists of a 70 thimble having a reduced central portion with inclined surfaces which so engage the loop of the rod that when the latter is placed under strain the share is tightly drawn into place and firmly connected with the mold-board and with the frog or block and the land-side. The slotted brace before referred to has inclined surfaces on opposite sides of the slot which are so formed as to cause the share to be firmly drawn into correct 80 position against the mold-board at its rear end and the finger carried by the share is of such shape and so located as to hold the front end of the share firmly connected with the land-side and the frog. 85

In the accompanying drawings:

Figure 1 is a perspective view of the underside of a plow embodying my improvements.

Fig. 2 shows a section on the line 2-2 of 90 Fig. 1.

Fig. 3 is a detail sectional view on the line 3-3 of Fig. 1.

Fig. 4 shows a section on the line 4-4 of Fig. 1, and illustrates how the looped end 95 of the connecting rod engages the projection on the share, the parts being in the position which they assume just before the lever is operated to put the rod under tension.

Fig. 5 is a view similar to Fig. 4 and shows the position of the parts when the lever is operated to put the connecting rod under tension.

Fig. 5^a is a detail sectional view, showing 105 the manner of attaching the projection to the share.

Fig. 6 is a detail sectional view on the line 6-6 of Fig. 1.

Fig. 7 is a perspective view, illustrating 110 how the brace carried by the land-side and mold-board is connected with the share.

Fig. 8 is a detail view showing the slotted end of the brace connected with the share. A portion of the plow beam or standard of the plow is indicated by dotted lines in Fig. 1 at A. B indicates the land-side, C the frog or bottom of the plow, and D the mold-board. The frog, mold-board and land-side may be secured together, in the manner indicated, or in any other suitable way. T indicates a brace commonly employed for connecting the upper end of the frog or bottom block of the plow with the mold-board. A brace E is attached to the upper end of the land-side and it is attached to the mold-board at F. This brace serves to hold the mold-board and land-side in proper relation and to withstand strains. The brace has an end e projecting beyond the edge of the mold-board and this projecting end of the brace is slotted, as indicated at e', and as shown in Fig. 7 the walls on the opposite sides of the slot are beveled or inclined, as shown at e''. To the inside of the mold-board is attached a bed-plate G to which the operating lever is connected. This bed-plate may be attached to the mold-board by a bolt g and also by a bolt g', which, as shown in Fig. 7, is carried by the mold-board and extends through an arm g'' on the lower or inner end of the plate. This arm is raised from the mold-board sufficiently to allow the brace E to extend beneath it, and the bolt g' passes through the brace and serves to hold its lower portion securely in place.

The operating lever H is pivotally connected at h to a standard I rising from the bed-plate. This standard is bifurcated, as shown in Fig. 3, and the lever H extends between the two members of the standard. One of these members is provided with a stop h' (Fig. 3) which limits the inward movement of the lever. As shown in Fig. 1 the standard I is formed with an enlargement i at the side of the lever H which in a measure prevents sidewise movement of the lever. To the lever H is attached an arm J which is bent at right angles, as shown, and then bent again to form a part j parallel with the inner portion of the lever H and this part j is formed with a bent end j' which bears against a brace K secured to the bed-plate. This brace has a curved surface, as indicated, against which the part j' bears, and the arrangement is such that as the lever is turned on its pivot it is prevented from sidewise movement, the strain on the lever being partially taken by the arm J and the brace K.

The connecting rod L is adjustably secured to a sleeve M, pivotally connecting to the lever H and the arm J at m. It will be observed that the end of the rod is threaded and it engages a tapped portion of the sleeve so that the rod may be adjusted end-

wise in the sleeve, to increase or decrease its length when desired by giving it one or more turns. The opposite end of the rod L is provided with a loop l which engages a projection N on the plow share O. This plow share may be of the usual general shape and it carries projections N and P and a finger Q. The finger Q is firmly connected with the plow share at q and it is bent so as to embrace the edge portion of the frog or block C and to also bear at x against the inner face of the land-side portion of the frog. When the plow share is drawn into place the finger overlaps the adjacent edge portion of the frog or block and also bears against the land-side portion of the frog in such manner as to hold these parts of the plow firmly connected. The projection P may be in the form of a bolt p attached to the share and carrying a washer p' and lock nut p''. The slotted end of the brace E engages this projection, in the manner clearly shown in the drawings. By forming the slot e' with inclined walls e'', a tight connection is afforded between the brace and the share. The frog C is formed with a slot c to receive the projection N.

Details of the projection N are shown more clearly in Figs. 4, 5 and 5^a. A thimble n, having flattened sides n' and a threaded opening n'', is secured to the plow share by a screw n³ which extends through the thimble and carries a lock nut n⁴. The thimble is formed with inclined surfaces n⁵ sloping from their outer ends inward toward the central portion of the thimble and adapted to receive the looped end of the rod L, in the manner indicated in Figs. 4 and 5 and also in Fig. 1.

The looped end of the rod may be easily engaged with the projection N when the lever is turned over toward the land-side of the plow. When the lever is reversed it will first draw the share to the position shown in Fig. 4. When power is applied to the lever so as to move it to the position shown in Fig. 2, by dotted lines, the looped end of the rod will engage the inclined surfaces n⁵ in such manner as to firmly draw the plow share into true position and firm connection with the mold-board and frog and the share will be held in this position as long as the lever is in the position shown in Fig. 2, the point of connection between the lever end of the rod being below the axis about which the lever turns.

It will be observed that the thimble n has flat opposite sides and is therefore adapted to receive a wrench which may be used for tightly fastening the thimble on the screw n³ and for tightening the connection should it tend to become loose.

By reference to Fig. 1 it will be observed that the connecting rod tightly holds the share in place when the lever is in the posi-

tion shown by full lines in Fig. 2. When the lever is turned to the position shown by dotted lines in Fig. 2 the connection is loosened and at the same time if the lever 5 is quickly operated the rear end l' of the loop will strike against the projection N and will cause the share to separate from the mold-board, frog and land-side.

In plows of the kind to which my invention relates, it is extremely important that not only the share be made readily detachable but that it should be firmly held in tight connection with the other parts of the plow when it is applied thereto. By my improvements this is done in the most efficient 15 way and by devices of the most simple and inexpensive character.

I claim as my invention:—

1. A plow, comprising a frog having a 20 slotted portion, a mold-board, a land-side, and a detachable share, and means for connecting the share with the frog, the mold-board and the land-side, comprising a projection on the share adapted to enter the 25 slot in the frog, a connecting rod having an

elongated loop engaging said projection, a bracket secured to the mold-board and carrying a bifurcated standard, a brace on the bracket, a lever pivotally connected with said standard and provided with an arm engaging the brace, and a connecting rod adjustably connected with the lever and having a looped end engaging a projection on the share. 30

2. A plow, comprising a frog, a mold-board and a detachable share, and means for connecting the share with the frog and mold-board, comprising a projection on the share, a connecting rod having a looped end engaging said projection, a lever connected with 35 the rod, a bed-plate attached to the mold-board, a bifurcated standard carried by the bed-plate to which the lever is pivotally connected, an extension on the standard for bracing the lever and a stop on the standard 40 for limiting the movement of the lever. 45

In testimony whereof I have hereunto subscribed my name.

RICHARD M. IVERSON.
